UNITED STATES PATENT OFFICE.

EARL W. FIALA, OF CEDAR RAPIDS, IOWA.

MAP-FOLDING MACHINE.

Application filed January 30, 1925. Serial No. 5,847.

To all whom it may concern:

Be it known that I, EARL W. FIALA, a citizen of the United States, residing at Cedar Rapids, in the county of Black Hawk 5 and State of Iowa, have invented certain new and useful Improvements in Map-Folding Machines, of which the following is a specification.

This invention relates to improvements 10 in means for folding and cutting sheet material, and is more particularly adapted to one for use in connection with the folding and cutting of maps.

One of the important objects of the present invention is to provide a map folding and cutting machine of the above mentioned character, which is of such construction as to effectively fold and cut maps in a manner that will save considerable time and 20 labor.

A further object of the invention is to provide a map folding and cutting machine of the above mentioned character, which will produce a folded and cut map of such 25 size as to enable the same to be carried in the pocket of a person without occupying any considerable amount of space.

A further object is to provide a map folding and cutting means of the above mentioned character, which is simple in construction, inexpensive, strong and durable, and further well adapted for the purposes 30 for which it is designed.

Other objects and advantages of this invention will become apparent during the 35 following description.

In the accompanying drawing, forming a part of this specification, and in which like numerals designate like parts throughout 40 the same:

Figure 1 is a top plan view of the map folding and cutting machine, embodying my invention.

Figure 2 is a side elevation thereof.

Figure 3 is a fragmentary view, showing the bottom die in plan, and

Figure 4 is a sectional view, taken approximately on the line 4-4 of Figure 3.

In the drawings, wherein for the purpose 50 of illustration is shown the preferred embodiment of my invention, the numeral 1 designates generally the frame, the same being substantially of rectangular design.

A bed 2 is arranged above the frame 1, as 55 clearly illustrated in Figure 2. A table,

such as is shown at 3, is associated with the forward end of the frame, and is disposed adjacent one of the side edges thereof. The purpose of the table will hereinafter be more fully described.

Complementary die members 4 and 5 are arranged above the bed 2 at the forward end of the frame. The die 4 is stationary and is provided with a pair of substantially V-shaped grooves 6 and 7 respectively, the same extending longitudinally of the die, as is clearly illustrated in Figures 3 and 4. The die 5 is provided with a pair of longitudinally extending substantially V-shaped cutting knives 8 and 9 respectively, the same 70 being adapted for cooperation with the V-shaped grooves 6 and 7 provided in the stationary die 4. The die 5 is adapted for vertical slideable movement with respect to the stationary die, and to this end the vertically extending guides, shown at 10, are provided, each guide having formed on the inner face thereof, a substantially dove tailed groove for receiving the dove tailed tongue 11, carried by each of the corners of 80 the movable die 5. This construction is more clearly illustrated in Figure 1. Normally the die 5 is spaced from the stationary die 4, and the operation of the die will be 85 hereinafter more fully described.

Cooperating feed rollers, such as are shown at 12 and 13 respectively extend longitudinally of the forward portion of the frame, adjacent the forward edge of the table 3, in the manner shown more clearly in Figure 90 4, the purpose of the rollers being to provide a means whereby the maps which are placed on the table 3 may be fed to the cooperating dies. The rollers are adapted to be rotated in opposite directions through 95 the medium of a pulley 14, which is associated with the outer end of one of the shafts of the feed rollers, preferably the upper one, the pulley 14 being in alignment with the pulley 15 supported on the forward end 100 of the longitudinally extending drive shaft 16, which is journaled in suitable bearings 17 on the front side of the frame. A belt 18 extends over the aligning pulleys 14 and 15 respectively. A suitable electric motor, designated generally by the numeral 19 provides a means for actuating the drive shaft 16.

Journaled at its respective ends in the upper ends of the vertical standards 20, ar- 110

ranged adjacent the ends of the frame 1 is a secondary drive shaft 21. A pulley 22 is mounted on the outer end of the secondary drive shaft 21, and is in alignment with the 5 pulley 23 mounted on the drive shaft 16, and over the pulleys is disposed a belt 24, whereby the secondary drive shaft will be driven by the main drive shaft 16. An eccentric 25 is secured on the secondary drive shaft 21, and a connection 26 is provided between the eccentric 25 and the top of the movable die 5, whereby the die will be adapted for vertical reciprocatory movement between the guides 10 when the secondary shaft 21 is 10 rotated, thus permitting the movable die 5 to cooperate with the stationary die 4, in cutting and creasing the map which is transferred from the table 3 by the feed rollers 12 and 13, onto the stationary die 4. It is 15 obvious that when the sharpened edges of the V-shaped cutting knives 8 and 9 carried by the die 5 are disposed within the V-shaped grooves 6 and 7, the map will be cut to a predetermined size and simultaneously 20 creased.

An ejector 27 is adapted for slidable movement on the intermediate portion of the stationary die 4, for the purpose of ejecting the map from the stationary die, after 25 the same has been cut and initially creased. The operating means for the slidable ejector 27 comprises a pin 28 which is secured at its upper end to the ejector and is adapted for slidable movement within the longitudinally 30 extending slot 29 provided in the central portion of the stationary die 4. The lower end of the pin 28 extends below the bottom of the stationary die, and a lever 30, which is pivotally supported, adjacent its rear end, 35 as illustrated at 31, below the table 3 is connected at its forward end to the lower end of the pin 28, as clearly illustrated in the drawings. The rear end of the lever 30 is pivotally connected to the forward end of 40 the longitudinally extending rod 32, and the free end of the rod extends outwardly from the side of the table for a suitable distance. The rod 32 is adapted for forward slidable movement by means of the cam 33, which 45 engages the free end of the rod 32. The cam 33 is supported on the rear end of a transversely extending shaft 34, which is journaled in suitable bearings below the said bed 2, and a pulley 35 is carried by the forward 50 end of the shaft 34, the same cooperating with a pulley 36 mounted on the drive shaft 16, through the medium of the belt 37. Normally the ejector 27 is disposed adjacent the forward end of the stationary die 4, as is 55 clearly illustrated in Figure 3. The same is adapted to move across the upper face of the intermediate portion of the stationary die 4, after the map has been cut and initially creased, and the ejector will engage the 60 map and move the same rearwardly off of 65

the stationary die, so that the map will be delivered to the funnel shaped guides 38 and 39 respectively, which are disposed at an incline above the bed 2, the upper ends of the funnel shaped guides being disposed in co-operative relation with the rear end of the stationary die adjacent the upper surface thereof, as is more clearly illustrated in Figure 2.

A pair of secondary creasing rollers 40 and 41 respectively, extend transversely across the bed 2 adjacent the lower ends of the funnel shaped guides 38 and 39. The ends of the shafts associated with the creasing rollers are journaled in suitable bearings 42 70 extending upwardly from the sides of the frame 1 and the creasing rollers are operated by means of the belt 43 and the pulley 44 mounted on the drive shaft 16.

Adapted to receive the map after the same 75 has passed through the creasing rollers 40 and 41 respectively, are the cooperating rotary folding members 45 and 46 respectively. Each of the folding members is star shaped in cross section, and the same extend 80 transversely across the rear end of the bed 2, the star shaped member 45 being disposed above the bed, while the complementary star member 46 is disposed below the bed. This is more clearly illustrated in Figure 2. The 85 shafts which carry the star shaped folding members are journaled at their respective ends in suitable bearings 47, which extend upwardly from the sides of the frame, and the folding members are adapted to be rotated through the medium of a belt 48 and the pulley wheel 49 mounted on the main 90 drive shaft 16.

After the map has passed through the star 95 shaped folding members, the folding operation has been completed, and the map is folded in such a manner as to enable the same to be readily inserted in the pocket of a person. The map is so folded as to enable 100 the same to be read like a book, when in use, and furthermore a compact package is provided, which will not occupy any considerable amount of space.

The purpose of disposing the creasing rollers and the folding rollers at substantially 105 right angles to the cutting and initially creasing dies is to obtain an alternate fold of the map.

It will thus be seen from the foregoing 110 description that a machine has been provided which will efficiently fold and cut maps in such a manner as to save considerable time and labor, and furthermore will be positive in its operation. Heretofore it has been necessary to employ a number of persons, in order to carry out the necessary steps in cutting and folding maps or other sheet material. The provision of a machine of the above mentioned character will obviate the 115 necessity of having to employ a number of 120 persons.

persons, it being only necessary to employ a single person for operating the present machine.

While I have shown the preferred embodiment of my invention, it is to be understood that various changes in the size, shape, and arrangement of parts may be resorted to, without departing from the spirit of the invention, and the scope of the appended claims.

Having thus described my invention, what is claimed is:

1. A machine of the class described comprising a frame, a stationary die supported at the forward end thereof, a complementary movable die cooperating with the stationary die for creasing and folding sheet material, means for feeding the sheet material to said dies, creasing rollers supported on said frame in cooperative relation with respect to said dies, folding means supported on the rear ends of the frame and cooperating with said creasing rollers, and means associated with the stationary die for ejecting the sheet of material therefrom, after the movable die has been moved out of engagement with the stationary die, whereby the material is delivered to said creasing rollers.

2. A machine of the class described comprising a frame, a stationary die supported at the forward end thereof, a complementary movable die cooperating with the stationary die for creasing and folding sheet material, means for feeding the sheet material to said dies, creasing rollers supported on said frame in cooperative relation with respect to said dies, folding means supported on the rear ends of the frame and operating with said creasing rollers, means associated with the stationary die for ejecting the sheet of material therefrom, after the movable die has been moved out of engagement with the stationary die, whereby the material is delivered to said creasing rollers, said last mentioned means comprising an ejector normally disposed adjacent the forward end of the stationary die, and adapted for slidable movement over the upper surface of the stationary die and engaging the sheet of material thereon.

3. A machine of the class described comprising a frame, a stationary die supported at the forward end thereof, a complementary movable die cooperating with the stationary die for creasing and folding sheet material, means for feeding the sheet material to said dies, creasing rollers supported on said frame in cooperative relation with respect to said dies, folding means supported on the rear ends of the frame and cooperating with said creasing rollers, means associated with the stationary die for ejecting the sheet of material therefrom, after the movable die has been moved out of

engagement with the stationary die, whereby the material is delivered to said creasing rollers, said last mentioned means comprising an ejector normally disposed adjacent the forward end of the stationary die and adapted for slidable movement over the upper surface of the stationary die and engaging the sheet of material thereon, and means for actuating the above mentioned movable elements.

4. A machine of the class described comprising a frame, a stationary die having a pair of substantially V-shaped grooves formed therein, a complementary die adapted for reciprocatory movement with respect to the stationary die, substantially V-shaped cutting members formed on the bottom of the movable die and adapted for cooperation with the V-shaped grooves in the stationary die, means for feeding sheet material to said dies, folding means arranged in cooperative relation with respect to said dies, and means for discharging the sheet material from the dies and feeding the same to said folding means.

5. A machine of the class described comprising a frame, a stationary die supported thereon, a complementary movable die cooperating with the stationary die for creasing and folding sheet material, means for feeding sheet material to said dies, creasing rollers supported on the frame in cooperative relation with respect to said dies, folding means cooperating with said creasing rollers, and means for discharging sheet material from said dies and feeding the same to said creasing rollers.

6. A machine of the class described comprising a frame, a stationary die mounted thereon and having a pair of substantially V-shaped grooves formed therein, a complementary die adapted for reciprocatory movement with respect to the stationary die, substantially V-shaped cutting members formed on the bottom of the movable die and cooperating with the V-shaped grooves in the stationary die for creasing and cutting sheet material, means for feeding sheet material to said dies, creasing rollers disposed at right angles to said dies and arranged in cooperative relation therewith, sheet folding means on the frame arranged in cooperative relation with respect to the creasing rollers, guide means for the sheet material disposed between the die and the creasing rollers, and means associated with said die for ejecting sheet material therefrom after the same has been initially creased and cut, whereby the sheet material is fed to said creasing rollers over said guide means.

In testimony whereof I affix my signature.

EARL W. FIALA.
